STEREOSCOPIC VIEWER

Richard L. Turner, Fort Myers, Fla.

Application July 30, 1954, Serial No. 31,676

Term of patent 3½ years

(Cl. D61—1)

FIG. 1.

FIG. 2.

Figure 1 is a top perspective view of a stereoscopic viewer, taken from the front thereof showing my new design; and

Figure 2 is a bottom perspective view thereof taken from the rear of the viewer.

I claim:

The ornamental design for a stereoscopic viewer, as shown.
